UNITED STATES PATENT OFFICE

HAROLD E. CHURCHILL, OF DETROIT, MICHIGAN.

TEMPERATURE-CONTROLLING DEVICE

1,377,750.

Specification of Letters Patent. Patented May 10, 1921.

Application filed July 3, 1916. Serial No. 107,422.

To all whom it may concern:

Be it known that I, HAROLD E. CHURCHILL, a citizen of the United States of America, residing at Detroit, in the county of Wayne 5 and State of Michigan, have invented certain new and useful Improvements in Temperature-Controlling Devices, of which the following is a specification, reference being had therein to the accompanying drawings.

10 This invention relates to temperature controlling devices and refers more particularly to an improved arrangement for automatically controlling refrigerating apparatus, although the invention in its broader 15 aspects is not necessarily limited to the particular use specified.

Among the objects of the invention are to provide means for automatically opening and closing an electric circuit or other controlling means upon any material change 20 from a predetermined relatively low temperature; to utilize an expansible diaphragm for making or breaking the circuit, this diaphragm containing a relatively low boiling 25 point liquid, such as sulfur dioxid; to provide a construction in which the diaphragm or other thermostatic member is operated by the expansion of saturated vapor, there being preferably sufficient of the liquid that 30 all of such liquid can not be vaporized before the pressure acts to stop further vaporization; to provide a refrigerator controlling device that can be economically manufactured and which will effectively 35 maintain the desired temperature; and in general to provide a new and improved controlling device of the character above referred to.

The invention further resides in such features of construction and arrangements and combination of parts as will more fully hereinafter appear.

In the drawings;

Figure 1 is a vertical sectional view 45 through a controlling device embodying my invention.

Fig. 2 is a top plan view of the parts shown in Fig. 1.

In the construction shown in the drawings, A designates the frame and B the expansible diaphragm which at its lower end is supported on a spider or plate member C. The latter is secured to the frame member

50 A by suitable bolts D extending through legs E. At its central por-

tion the casing A is provided with an inverted cup-shaped member F which is apertured at its upper end and provided with a tubular stem G. This stem is exteriorly threaded at J, and interiorly threaded at 60 H, there being a longitudinally-adjustable tubular stem L positioned within the stem G and having threads I engaging the threads H. Thus upon turning the head M of the stem L, the latter can be adjusted toward 65 or from the diaphragm B.

The stem L in turn forms a bearing for the longitudinally-adjustable rod N, the lower end of which rod is secured to a shoulder or abutment member B' on the expansible diaphragm B. At its upper end the rod N terminates adjacent and in alinement with the operating stem O of a push button switch O'. This switch is carried by a support P screw threaded onto the stem G and 70 can be locked in various positions of adjustment by a lock nut P'. Arms P² and P³, preferably formed integral with the support P carry a bearing member P⁴ into which the support for the switch O' is screw threaded. 80

Normally the parts are in the position shown in Fig. 1, the switch O' being held open by the action of the spring O². When, however, the desired temperature is exceeded, the expansion of the diaphragm will 85 lift the rod N against the stem O and raise the latter until the switch is closed to complete the circuit through the terminals Q and Q'. The closing of the electric circuit in this manner can be utilized for governing 90 the action of the refrigerating apparatus, the detailed arrangement of which forms no part of the present invention since any electrically or manually operated device capable of use with refrigerating apparatus, can be 95 employed.

The present invention however particularly contemplates the use of a diaphragm, of a fluid having a relatively low boiling point, so that where a temperature below 100 that at which water freezes is desired, a saturated vapor can still be employed for operating the switch. For this purpose I have found that sulfur dioxid is particularly well adapted since it boils at about 14° 105 Fahrenheit when under atmospheric pressure and an increase in temperature produces a definite increase in pressure.

For maintaining the pressure on the diaphragm, a spring R is employed, one end of 110

this spring abutting against the upper surface of the diaphragm and the other end against an abutment R' on the end of the stem L. Thus the tension of the spring can be varied and also the distance between the end of the rod N and the stem O of the switch so that the proper operative relation between the parts may be reestablished after any adjustment of the spring R.

10 The invention however, is not limited to the details of construction nor to the use of sulfur dioxide, since other substances having the desired qualities might be substituted therefor within the scope of my invention.

15 What I claim as my invention is:
In a temperature controlling device, the combination with a thermostat having a

heat responsive member, of a rod longitudinally actuatable by said member, a casing for said member, a tubular stem mounted 20 on said casing surrounding said rod, a second tubular stem embracing said rod within the first mentioned tubular stem and longitudinally adjustable therein, a mounting longitudinally adjustable upon the outer 25 stem, a member engageable by said rod carried by said mounting, an abutment carried by the inner stem within said casing and a spring compressed between said abutment and the heat responsive member resisting 30 expansion of the latter.

In testimony whereof I affix my signature.

HAROLD E. CHURCHILL.
